FLANGE OILER

Olof W. Swanson, Chicago, Ill.

Application December 23, 1938, Serial No. 247,327

6 Claims. (Cl. 184—3)

This invention relates to flange oilers for lubricating wheel flanges more particularly of railroad locomotives.

Among other objects, the invention provides an improved oiler of this class which insures more positive and uniform oiling of the flange and flange only of the wheel, at reduced cost of manufacture and operation.

Specifically, this invention is an improvement upon my Patent No. 1,942,847 of January 9, 1934, and is adapted especially for locomotives which are engaged in long run and high speed service.

Other objects and advantages will be apparent from the following description, taken together with the accompanying drawings, in which—

Figure 1 is a somewhat schematic view, showing my improved flange oiler applied to the locomotive wheel;

Figure 2 is an enlarged elevational view, partly in axial section, of the oil reservoir;

Figure 3 is an enlarged view taken on the line 3—3 of Fig. 1 with the feed pipe removed;

Figure 4 is a section of the structure of Fig. 3 taken on the staggered line 4—4;

Figure 5 is a cross-section taken on the line 5—5 of Fig. 4; and

Figure 6 is a view somewhat similar to Fig. 5, but on a smaller scale without being in section, and showing alternative positions of the parts.

Referring in detail to the illustrative construction shown in the drawings, 10 indicates a conventional locomotive driving wheel having the tire 11 provided with the usual tread 12 and flange 13.

It is desirable to prevent unnecessary noise and wear, and sometimes climbing of the flange on the rail, to have an adequate but not too large amount of lubrication provided on the flange of the wheel along the area of the flange between the top 14a of the flange and the throat 14b where the tread and flange meet (Fig. 6). Too much oil must not be deposited since it might reach the tread of the wheel, which would be objectionable as tending to reduce the traction or drawing power of the locomotive. Such lubrication as is provided should be uniform and positive in both quantity and exactly proper location of application.

To effect improved lubricating means functioning in accordance with these requirements, I have provided the device indicated in general by the numeral 15 and comprising, in accordance with my present invention, the distributor shoe 16 which contacts the flange 13 of the wheel 10.

The distributor shoe 16, in this instance, is a

somewhat heavy casting having a flange embracing portion 17 which is of somewhat block form, and a mounting portion 18 in the form of an integral leg. The distal end 19 of the flange embracing portion of the shoe, as best shown in Figs. 5 and 6, is recessed by a groove 20 conforming complementarily to the flange 13 of the wheel and receiving the flange when the shoe is held radially against the flange, as here shown and as later described, thus embracing the flange but permitting the flange to run freely therethrough as the wheel revolves in the progress of the locomotive along the track.

The side 21 of the shoe which faces the tread 12 of the wheel is desirably somewhat longer than the rear side 22, and the distal end 23 of this side is desirably curved convexly, as shown, to somewhat conform to the throat 14b of the wheel or point where the flange meets the tread. Also, this curved end avoids a sharp edge on the shoe 20 as does also the rounded end 24 of the rear side of the shoe.

To cause the oil to reach the area of the flange between its top 14a and throat 14b, this being the area along which the distal portion 23 of the face 21 lies, the block 17 has a passageway therethrough communicating with the distal end of the shoe and particularly with the distal portion 23 at the tread-facing side of the flange. This passageway, in this instance, comprises a restricted bore 25 communicating at its upper end with an inlet 26 opening through the tubular portion 27 of the shoe, and at the lower end with the slot 28 in the face 21, both the inlet 26 and slot 28 being thus continuations of the bore 25. Thus, 35 the slot 28 opens transversely into the groove 20.

So constructed and arranged, the oil carried in the oil reservoir 29 passes down by gravity through the feed pipe 30 and into the bore of the shoe, the discharge end of the pipe 30 communicating 40 by means of the nipple 31 with the inlet 26, the nipple 31 being threadedly received in the tubular portion 27 of the shoe. The oil passing through the restricted bore 25 is distributed, by gravity and capillary attraction as well as by vibration of the shoe, along the walls of the slot 28, and then over a substantial circumferential segment of the area of the flange referred to, by means of the distal end of the shoe. The slot 28 desirably spaces the restricted bore 25 from the ultimate distal end 50 of the shoe, and furthermore this slot being open laterally at one side of the shoe, no dirt or other obstruction accumulated on the flange or distal end of the shoe can reach the restricted bore 25, and furthermore any such dirt or obstruction 55

would fall out through the open slot and not accumulate therein to cause stoppage, this function being assisted by normal vibration of the shoe in operation, which is very important to 5 its success.

The slot 28 is desirably undercut as at 28a upon its lower side to facilitate running of the oil therefrom to the throat of the flange.

Both to further restrict the bore 25 and at the 10 same time to maintain a passageway there-through, though restricted, for the oil, I have provided a vibrating member therein such as the rod 32 which is resiliently supported in the bore 25 as by being hung on the light helical spring 15 33 to depend loosely within the slot 28 and desirably to lightly contact the flange within the area referred to. Thus vibration of the shoe in response to movement of the wheel will jiggle the rod 32 and keep the bore 25 free from dirt 20 or other obstruction. Also, some portion of the oil may advantageously descend along the cylindrical surface of the rod 32 to reach the flange in this additional manner.

Further in accordance with my invention, the 25 shoe 16 is mounted for reciprocal and rocking limited movement so as to follow the movements of the wheel both radially and transversely, and also to accommodate itself to wear of the flange which changes the contour of the flange, and 30 also to different diameters of the wheel tire. As is well known in the art, wheel tires, or the complete wheels, may be removed at intervals when wear of the flange becomes too pronounced, to re-turn as on a lathe the tread and flange to 35 produce a new tread and flange on the same tire by cutting away sufficient of the old tread and flange to restore the proper contour thereby.

For such mounting purposes, the leg 18 constitutes an integral mounting portion of the shoe 40 16 and as here shown, extends upwardly from one side of the shoe, that is, a narrower side at right angles to the faces 21 and 22. It is therefore offset laterally of the bore of the shoe and is aligned with the flange receiving groove 20. This 45 flat leg 18 is slidingly received in the channel 34 of the rocker pad 35 and is retained therein by the keeper plate 36 which is bolted as at 37 on the bosses 38 which form a part of the wall of the channel 34 of a height from the bottom of 50 the channel approximately equal to the thickness of the leg 18. The rocker pad 35 is suitably fixedly attached to the locomotive frame 39 in the vicinity of the wheel flange, as in this instance, by being carried by the bracket 40 which 55 has one angular part 41 which may be welded to the locomotive frame at 42 and another angular portion 43 which extends out transversely over the wheel flange. The rocker pad 35 is then fastened to the bracket portion 43 of the bracket 60 40 as by bolts 44 and 45, so that a plane passing through the leg 18 and groove 20 substantially centrally thereof also passes substantially centrally through the top of the flange 13 of the wheel and parallel to the general plane of the 65 wheel. The three point support afforded by the two bolts 44 and 45, together with the fact that these bolts pass through two of three bosses 35a which space the rocker pad from the bracket portion 43, facilitates centering of the rocker pad 70 on the bracket in this position, and also causes the rocker pad to adapt itself to the plane of the bracket when the pad is being bolted into place.

Thus, the distributor shoe, by reciprocal movement of the leg 18 in the channel 34, accommo-

dates itself to the radial position of the flange. In practice, the bracket 43 will be located sufficiently close to the top of a new flange so as to be well out of any possible contact therewith, but so that the leg 18 of the shoe will project at 5 its upper end well above the rocker pad 35, and permitting the shoe to drop by gravity as the flange and distal end of the shoe are worn off by abrasion. A lug 46 at the top of the leg 18 which would engage the keeper plate 36 if the 10 shoe were sufficiently lowered in the channel, prevents the shoe from being separated from the rocker pad accidentally, as for example should the wheel be removed entirely. The block 17 of course by possible engagement with the 15 keeper plate 36, limits reciprocal movement of the shoe in the opposite radial direction.

For appropriate rocking purposes to permit the shoe to accommodate itself to transverse movements of the wheel, as indicated in Fig. 6, 20 the channel 34, further in accordance with my invention, is flared at both its upper and lower ends from a point intermedial of the length of the channel, such as 47, where the channel is of a width substantially that of the leg 18. Thus 25 the points 47 where the sides of the channel are closest together act as fulcrums upon which the shoe rocks to accommodate itself to said transverse movement. The walls 48 of the channel, however, limit such movement while permitting 30 a maximum extent thereof sufficient to provide for any normal or even slightly abnormal transverse movement of the wheel. So constructed and arranged, the shoe throughout the operation of the device continues to embrace the flange 35 of the wheel, so that the oil is positively delivered to the proper location on the flange at all times. Furthermore, the oil is wiped onto the flange instead of being merely dropped thereon, which prevents wind and centrifugal force from blowing 40 the oil away from the flange.

As best shown in Fig. 1, the bracket 40 is advantageously mounted so that the shoe 16 is directed radially of the wheel 10 but along a radius 49 which is at an angle of approximately forty-five degrees to a radius 50 passing vertically through the top of the wheel. Thus, the weight of the shoe 16 is not entirely carried by the flange, but is distributed between the flange and the bracket 40, the angle which the shoe thus occupies to the horizontal being just a little more than the angle of repose of the shoe on the bracket.

Referring to Fig. 2, it will be understood that the reservoir 29 may be suitably secured, as by 55 bolts (not shown) passing through its drilled arms 51, to an appropriate location on the locomotive frame, and vibration of which causes the ball valve 52 to permit a limited and substantially predetermined quantity of oil to pass downwardly through the feed pipe 30. As more particularly described and claimed in my Patent No. 1,942,847, this predetermined of the amount of oil is assisted by the novel device 53 which is loosely retained in the restricted passage 54 from 60 the reservoir to the feed pipe, and is movable by oscillation of the oil in the reservoir to maintain the passage open though restricted. The reservoir may be filled by removal of the closure cap 55 and may be drained by removal of the 65 plug 56. Also, if desired, a steam chamber 57 may be provided for heating the oil during cold weather, as by having exhaust steam passed therethrough by connections 58 and 59.

The shoe will of course wear, but due to its 75

novel construction and operation it will advantageously wear at its distal end to a shape always conforming to the shape of the flange; that is, if for example, the wheel flange wears thinner, the groove 20 will wear correspondingly deeper but narrower. When the shoe becomes badly worn, it may readily be replaced by removing the keeper plate 36 and substituting a new shoe.

The invention is not limited to details of construction shown for purposes of illustration. Furthermore, it is not essential that all features of the invention be used conjointly, as various combinations or sub-combinations may be advantageously employed.

Such changes may be made as fall within the scope of the following claims without departing from the invention.

Having described my invention, I claim:

1. A wheel flange oiler including a distributor shoe embodying a heavy metallic casting of somewhat block form, the distal end thereof having a recess shaped to conform generally to and for receiving the flange of the wheel and the proximal end thereof being adapted to have connected thereto an oil feed pipe, said shoe having a bore therethrough communicating with said ends, and the face of the block toward the tread of the wheel having a slot therein providing a pair of fingers at each side laterally of said bore, said slot providing a continuation of the bore.

2. A wheel flange oiler including a distributor shoe embodying a heavy metallic casting of somewhat block form, the distal end thereof having a recess shaped to conform generally to and for receiving the flange of the wheel and the proximal end thereof being adapted to have connected thereto an oil feed pipe, said shoe having a bore communicating with said ends for discharging oil therethrough and a slot-like enlargement of said bore at said distal end on the tread side of the flange, and wherein a light rod is resiliently suspended to pass somewhat loosely through said bore and depending within the slot-like enlargement to lightly contact the flange short of the ultimate distal end of the shoe.

3. A wheel flange oiler comprising an oil distributor shoe having a flange embracing portion, an open slot in the face of the shoe toward the tread side of the wheel, a restricted bore communicating with said slot, and a member loosely carried by the shoe within said restricted bore and adapted to vibrate under movement of the shoe to maintain said bore free for the passage of oil, said member terminating short of the termi-

nation of the flange embracing portion but exposed in said slot.

4. In a wheel flange oiler, the combination with a distributor shoe having a groove therein receiving the flange, of mounting means for the shoe including a bracket having a channel flared at its lower end transversely of the flange, a mounting portion for said shoe slidably received in said channel and substantially the width of said channel at its upper end whereby the shoe while so mounted may follow the flange both radially and transversely thereof, and a keeper plate retaining said mounting portion in said channel.

5. In a wheel flange oiler, the combination with a distributor shoe having a groove therein receiving the flange, of mounting means for the shoe including a member having a channel flared at its lower end transversely of the flange, a mounting portion for said shoe slidably received in said channel and substantially the width of said channel at its upper end whereby the shoe may follow the flange both radially and transversely, a bracket carrying said member on a three-point support, and means retaining said mounting portion in said channel.

6. In a wheel flange oiler, the combination with oil supply means, of a member mounted transversely of the wheel flange on the upper side of the wheel on an angle approximately forty-five degrees to a vertical plane passing through the axis of the wheel, a channel in the upper side of said member having a narrow part and flared transversely of the flange above and below said narrow part, a distributor shoe having a mounting leg in said channel of substantially the width of the said narrow part and slidably therein both radially and transversely of said flange, a distributor portion of said shoe integral with said mounting portion and offset thereof along the flange, said distributor portion having an oil passage therethrough connected with said oil supply means and a restricted bore therein, the shoe having a distal end adapted to contact the throat of the flange, a vibrating rod loosely mounted in said restricted bore and terminating short of the distal end of said distributor shoe portion, a flange receiving groove in said distal end extending beyond said vibrating rod, and an open slot in the face of the shoe toward the wheel tread opening into said flange receiving groove and said restricted bore, said vibrating rod being partially exposed in said slot and said slot being undercut on its lower side radially aligned with the throat of the flange.

OLOF W. SWANSON.
